UNITED STATES PATENT OFFICE.

ALFRED M. HARRIS, OF DETROIT, MICHIGAN.

TOY.

1,217,865.

Specification of Letters Patent.

Patented Feb. 27, 1917.

Application filed March 23, 1916. Serial No. 86,203.

To all whom it may concern:

Be it known that I, ALFRED M. HARRIS, a citizen of the United States, residing at Detroit, in the county of Wayne and State 5 of Michigan, have invented certain new and useful Improvements in Toys, of which the following is a specification.

This invention relates to automatic toys and has for its primary object to provide a 10 toy that will stimulate amusement for children by carrying loads of material up an incline and automatically dumping the same.

Another object of this invention is the provision of a toy provided with a car adapted to be hauled upon an incline, and the contents dumped from the car with provision for conducting the contents from the dumping position to the starting point of the car.

20 A further object of this invention is the provision of a toy which will contain instructive as well as amusing mechanical movements and appliances and which will be instructive to both young and elderly people.

25 A further object of this invention is the provision of a toy which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which:

Figure 1 is a side elevation, parts being shown in section.

40 Fig. 2 is a top plan view.

A plurality of uprights or supporting posts 1 are provided which vary in length in order that the track 2 which is mounted thereon will be disposed at an angle. Each 45 of the members which go to form the rails of the track are provided with loops 3 which depend from the track in an arcuate form as clearly indicated by Fig. 1 of the drawing.

50 Cross braces 4 are arranged on each of the supporting posts 1 and are provided with guide pulleys 5 which have a bearing in the center of the cross braces 4. A car 6 is provided, and in order that it may 55 travel upon the track 2, a front truck having wheels 7 is mounted at the forward

end thereof, while the rear truck is provided with wheels 8 which are mounted adjacent the rear of the car. The wheels of the front truck are considerably smaller in diameter 60 and in width of face than the wheels of the rear truck. A flange 9 is provided on the wheels 8 of the rear truck in order that the car may be guided and held upon the tracks.

The car is also provided with a bail 10 65 which is pivoted at 11 and attached to the bail is a rope or length of twine 12 which is guided over a sheave 13 rotatably mounted at the extreme upper end of the track 2. A windlass 14 is mounted on the base of 70 the toy and upon which the rope 12 is adapted to be wound. A crank handle 15 is provided at the end of the windlass 14 so that rotation may be imparted to the windlass for the purpose of winding the rope 75 thereon, thereby drawing or hauling the car 6 upon the inclined track. A pawl and ratchet 16 of the ordinary construction is provided on the windlass so that the car may be stopped at any desired position upon 80 the track 2.

It will be observed that the loop which depends from the track 2 is of a width sufficient to receive the wheels of the front truck of the car, but not wide enough to 85 receive the wheels of the rear truck. When the car is made to travel up the inclined track the front wheels will be received by the loop and by continuing to wind the windlass, the car will proceed to turn almost completely over and by virtue of the wider wheels of the flanged members of the rear truck will be held practically in an inverted position as shown by the dotted lines in Fig. 1. 95

Secured to the track 2 is a receptacle 17 which is large enough to receive the material when it is dumped and also the car itself. The bottom of the receptacle 17 is inclined toward the center of the receptacle and secured thereto is a flexible tube 18 through which the contents of the receptacle is adapted to be conducted to the starting point of the car. The tube 18 is fixed thereto and adjacent to its free end is a valve 19 which is adapted to be opened and closed for releasing the material as it goes through the tube when it is desired to refill the car. It is of course understood that the same material is to be used over and over again and 110 by this construction the car carries this up the inclined track and by means of the tube

18, the same material is carried back to the starting point of the car where it is again deposited within the car ready for another trip up the inclined track.

5 From the foregoing it will be observed that a very simple and durable toy has been provided, the details of which embody the preferred form. I desire it to be understood however, that slight changes or modifications in the minor details of construction 10 may be made without departing from the spirit of the invention or the scope of the claims hereunto appended.

I claim:

15 A toy comprising an inclined track, the said track being provided with loops near its upper end, a receptacle suspended from the tracks and having the said loops dis-

posed therein, a car mounted upon the tracks the front wheels of which are adapted to be received by the said loops, the rear wheels of the car being of a diameter greater than the width of the loops whereby the said rear wheels will pass over said loops, for inverting the said car and disposing the same into said receptacle, a tube connected to the receptacle and terminating at the starting point of the car, and means connected to the car for drawing the same up the inclined tracks.

In testimony whereof I affix my signature in presence of two witnesses.

ALFRED M. HARRIS.
